UNITED STATES PATENT OFFICE.

LOUIS SCHNEIDER, OF WILLIAMSPORT, PENNSYLVANIA.

SASH-TIGHTENER.

SPECIFICATION forming part of Letters Patent No. 241,072, dated May 3, 1881.

Application filed March 31, 1881. (No model.)

To all whom it may concern:

Be it known that I, LOUIS SCHNEIDER, a citizen of the United States, residing at Williamsport, in the county of Lycoming and State of Pennsylvania, have invented certain new and useful Improvements in Self-Adjusting Sash-Tighteners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective, showing the present invention applied to use. Fig. 2 shows the several parts or pieces of which the tightener is composed; Fig. 3, vertical central section of the roller, &c.

The object of this invention is to produce a simple, cheap, strong, self-adjusting window-sash tightener; and the novelty consists in the peculiar construction of the several parts, and in their combination together to form the present device, all, as will now be more fully set out.

In the accompanying drawings, A denotes any window-sash stile having a mortise or socket, *a*, on the edge of said stile, of suitable shape and size to contain the tightener. This socket is open on one side at *a'*, to allow the tightener to operate against the guide-strip *r*. The plate B of the tightener is secured in the socket *a* by means of a bolt or screw, *b*, through its upper end, and will thus be capable of a swinging motion on said bolt or screw as a pivot. In the body of said plate is a boss or post, *b'*, on which the roller C, having a central opening, *c*, fits, so that it can rotate freely; also,

of course, having a swinging motion from plate 40 B, on which it is secured. To this swinging plate B, and so as to be above and free from the roller C, is secured a socket, D, to hold the reversible spring E.

When, now, the device is thus made and applied to use, the spring E, acting against the walls of the socket *a*, will serve to press out the plate B, and thus carry the roller C against the guide-strip, and in this way effectually prevent the sash from rattling, and exclude air and 50 dust.

If desired, the periphery of the roller C may be flanged on its outer edge, and have upon it and inside of the said flange a rubber or anti-friction band, D, as shown in Fig. 3. The spring 55 E will fit into either side of the seat D, and the spring can easily and quickly be inserted in said seat so as to come on either side of the roller, and thus the device may be readily applied in a right or left hand socket.

As thus made and constructed the device is simple, strong, readily applied, and most efficient in its operations.

Having thus described my invention, what I consider new, and desire to secure by Letters 65 Patent, is—

A window-sash tightener composed of the following elements or parts, viz: the pivotal plate B, having a boss, *b'*, the spring-socket D, roller C, and reversible spring E, all constructed and operated substantially as and for the purposes set forth.

In testimony whereof I affix my signature in presence of two witnesses.

LOUIS SCHNEIDER.
